ST. LOUIS CHILLED BEARING COMPANY, OF ST. LOUIS, MISSOURI, A CORPORATION
OF MISSOURI.

MOLD.

1,163,135.

Specification of Letters Patent.

Patented Dec. 7, 1915.

Application filed April 13, 1912. Serial No. 690,615.

To all whom it may concern:

Be it known that we, FRANK J. FRIESE and JOHN E. GILBERT, citizens of the United States of America, residing in the city of St. Louis and State of Missouri, have invented 5 certain new and useful Improvements in Molds, of which the following is a specification.

This invention relates to molds, preferably metallic ones, for making journal bearings or brasses; and has for its primary object means for preventing "cold shot" in the lower part of molds.

Another object is to provide means whereby the point of contact of flowing molten metal against the inner portion of the mold is always changing.

Another object is to prevent deterioration of the inner walls of the mold.

20 A still further object is to provide a mold in which the consistency of the molded metal is not changed during the molding operation.

Other and further objects will appear in 25 the specification, and be specifically pointed out in the appended claims, reference being had to the accompanying drawings, exemplifying the invention, and in which,

Figure 1 is a plan view of this improved 30 mold. Fig. 2 is a section taken approximately on the curved line II-II, Fig. 1. Fig. 3 is a horizontal section on the line III-III, Fig. 2. Fig. 4 is a perspective view of a journal bearing immediately after 35 its removal from the mold.

1 designates the drag and base of a sectional mold, having hinge members 2 integral therewith. The sectional copes 3 and 4 carry hinge members 5, and are hingingly 40 secured to the hinge members 2 by the pins 6. Said cope sections 3 and 4 are locked together by a clamp 7 engaging the lugs 8, said lugs 8 being integral with the cope sections 3 and 4. As shown in Fig. 3, the casting or molding chamber 9 is formed with the inner recess 10 in the drag 1, and the outer recesses 11 and 12 formed in the sectional copes 3 and 4.

Located on one end of the casting chamber 9, and practically in alignment with said casting chamber, is an ingate 13 having communication to the molding chamber 9 through the vertical inlet 14, said inlet being the approximate depth or length of the 55 molding chamber 9. The lower end of the

ingate 13 is curved inwardly to the mold chamber 9, as shown at 15. The ingate 13, as shown, is in the cope 4, and when in the position shown in Fig. 3, in which the mold is ready for pouring, has a facing against a 60 portion of the drag, as shown at 16.

The riser 17 is located at the center of the mold, being formed by the recess 18 in the drag and the recesses 19 formed in the sectional copes 3 and 4.

Heretofore, in the pouring of bearings, especially brasses, "cold shot" forms in the bottom of said brasses by reason of the initial pour becoming chilled and settling at the bottom of the mold. This improvement, which lies especially in the ingate, 70 entirely overcomes this condition by reason of the ingate leading to the bottom of the mold. The initial pouring will be washed up from the bottom of the mold by reason 75 of the onrush of the continuous pouring. And also by reason of the vertical inlet extending from top to bottom, there will be practically an unbroken flowing current 80 taking place entirely through the mold until the pouring is completed. Then, the molded mass proper will cool in unison, making a good clear bearing, and no "cold shot."

Also, because the vertical inlet 14, leading from the ingate 13 into the mold chamber, 85 is located at one end of the mold chamber, and in alignment therewith, the "spot heating" trouble is overcome. Inasmuch as the inlet 14 is a continuous opening, and is in the direct line with the chamber 9, the flowing point of the molten metal, when entering the mold chamber, is always changing. And, furthermore, as the mold is becoming 90 filled with the molten metal, there will be a rise or moving of the entering point of the 95 molten metal into the mold proper, thus leaving no one set pouring point of the molten metal striking the mold during the operation. This changing of the flowing point of the molten metal is very essential, 100 as when the molten metal strikes the inner portion of the mold at one continuous point, that portion of the mold expands greatly, making an ununiform expansion and contraction of the mold. Deterioration also 105 takes place by reason of the continued high heating of the one spot at which point the flowing metal engages the old types of metallic molds. And, furthermore, the carbon, that is given off from metallic molds by this 110

intense heat, enters and mingles with the molten metal, thereby making an inferior casting or brass.

Fig. 4 shows a bearing casting immediately after being removed from the mold, which indicates very clearly the location of the ingate in relation to one of the ends of the casting chamber.

What we claim is:

- 10 1. A mold comprising a mold chamber, an ingate leading to the bottom of said chamber, and a continuously formed vertical inlet passageway located between said ingate and said chamber adapted to establish continuous communication from said ingate to said chamber throughout the depth of said chamber.
- 20 2. A mold comprising foldable sections, said sections when folded together adapted to form a mold chamber, said mold chamber having an ingate leading to the bottom thereof, a vertically arranged continuously open inlet passageway located between said ingate and said mold chamber, said vertical inlet being the length of the approximate depth of said mold chamber, and adapted to form means of continuous communication between said ingate and said mold chamber.
- 25 3. A mold composed of three sections, two of said sections being swingingly secured to said other section, said swinging sections

when moved against said other sections forming a mold chamber, an ingate leading to the bottom of said mold chamber formed in one of said swinging sections, and a vertically arranged inlet passageway located between said ingate and one end of said mold chamber adapted to establish continuous communication between said ingate and said mold chamber throughout the depth of 40 said mold chamber.

4. A mold composed of two matching sections forming a mold chamber, an ingate arranged adjacent to the mold chamber and extending to a point on a plane with the bottom of said mold chamber, a restricted passageway of the approximate length of the depth of said mold chamber arranged between said ingate and said mold chamber, said restricted passageway adapted to establish communication between said ingate and said mold chamber throughout the approximate length of said ingate, substantially as specified.

In testimony whereof, we have affixed our signatures, this 3rd day of April, 1912.

FRANK J. FRIESE.
JOHN E. GILBERT.
